United States Patent Office

Des. 218,139

Patented July 28, 1970

218,139

AIRCRAFT FUEL SUMP DRAINING TOOL

Taso P. Anthan, 3207 NW. Oakcrest Drive,
Kansas City, Mo. 64151

Filed Dec. 24, 1968, Ser. No. 15,108

Term of patent 14 years

Int. Cl. D8—02

U.S. Cl. D8—16

Fig. 1.

Fig. 2.

Fig. 3.

Fig. 4.

Fig. 5.

FIG. 1 is a front elevational view of the aircraft fuel sump draining tool;

FIG. 2 is a side elevational view thereof;

FIG. 3 is a top plan view thereof;

FIG. 4 is a bottom plan view; and

FIG. 5 is a perspective view showing the side opposite to that shown in FIG. 1.

I claim:

The ornamental design for an aircraft fuel sump draining tool, as shown and described.
